Application December 5, 1929, Serial No. 411,831,
and in Great Britain December 7, 1928. Re-
newed October 26, 1931

61 Claims. (Cl. 179—18)

The present invention relates to telephone systems and is more particularly concerned with multi-exchange systems comprising a number of exchanges of small capacity. Considerable difficulty has been experienced in devising economical arrangements for providing automatic service to a network of exchanges which are widely separated and which each comprise only a small number of lines, for instance 20 or 30, as may well occur in rural districts. It is the chief object of the present invention to provide an improved arrangement for giving service in these circumstances with the minimum of equipment and great economy in the number of trunk lines required.

In order to enable the trunking arrangement to be as flexible as possible, the system according to the invention contemplates the use of register translators which will respond to the initial digits of the exchange name, for instance, the first two, and translate these digits into a routing number which can be chosen to permit the most efficient trunking arrangements and which can subsequently be altered if desired without affecting the subscribers' numbers. Equipment of this nature is, however, costly, and owing to the small size of the exchanges of the type considered it would need to be provided in such quantities as to be uneconomical if translating equipment were located at each exchange. According to the invention, therefore, the translating equipment is centralized at an exchange in the network which is most suitably placed geographically in relation to the other exchanges and a number of exchanges employ this translating equipment in common.

According to another feature of the invention the translating and so-called tandem equipment is made up into a separate unit, which is kept distinct from the local switching equipment in that exchange, whereby the local equipment may be the same in all exchanges and it is only necessary to add the tandem equipment in the exchange which by virtue of its size and position is most suited to receive it.

According to a still further feature of the invention, metering arrangements are provided in which the meter is operated singly or a number of times for each call or period of time elapsing during the progress of the call, depending on the zone in which the called subscriber's exchange is situated. A further feature of the invention concerns a 25 point rotary switch, functioning as an outlet selecting switch which is operated by a single series of impulses sent out by the register translator.

The invention will be better understood from the following description of the circuit arrangements, reference being made to the accompanying drawings comprising Figs. 1 to 9 which should be arranged as follows: Fig. 2 should be placed to the right of Fig. 1 and Fig. 3 to the right of Fig. 2. Figs. 4, 5 and 7 should be placed below Figs. 1, 2 and 3 respectively and Fig. 8 to the right of Fig. 7, Fig. 9 should be placed in a position below Figs. 7 and 8, while Fig. 6 should be placed below Figs. 4 and 5. The interconnecting lines will now be found to be in alignment and a complete circuit of the invention is thus obtained. This arrangement, however, is given by way of example only, since it will readily be apparent to those skilled in the art that the principles of the invention are capable of wider application and are not limited to the precise arrangement shown.

Referring now more particularly to the drawings, Fig. 1 shows a subscriber's line circuit and a link circuit at the local exchange. Figs. 2 and 3 show further portions of the link circuit, whilst Fig. 3 also includes (to the right of the dotted line) metering equipment common to a number of link circuits. Fig. 4 shows the circuit of the junction extending to the tandem office; Fig. 5 shows the circuit of the tandem 1st Code Selector; Fig. 6 shows the switch employed for calls incoming over the junction, and Figs. 7, 8 and 9 show the circuit of a register translator.

A description will first be given of the establishment of a connection between a calling subscriber "A" whose number is 2121, and a wanted subscriber "B" in another automatic exchange, whose number we will assume to be 3333.

In order to simplify the tracing of the circuits through the various drawings, the following table sets out the relays which are located in each figure:

1	2	3	4	5	6	7	8	9	
L CO	AD BD	SP ST	CS KA	SA SB	BA BB	DAS DAK	DR DTP	DCA DAD	100
A B C K S M CA DA DB	CD C MB F H CB CH TD E G	MA MB MV MW MX MY		SC SD SE SG SH SI SK SL SM SW SEA SLA SLB	BC BD BE BF BG BH BS BAD BBD BCD	DDA DDB DDC DC DCO DBR DVR	DPR DS DSA DSZ DRA	DBD DCD	105
									110

When subscriber "A" removes his receiver, re-

- lay L is operated over its upper winding in series with the subscriber's instrument. Thereupon at armature l_2 it removes earth from the associated contacts in the banks of the line finder switches 5 such as FS so as to render the line selectable and also prepares a circuit for the cut-off relay CO; at armature l_1 it disconnects the cut-off relay from one of the speaking conductors and at armature l_3 completes a circuit extending over conductor 10 15, wiper 110 of the distributor DA and conductor 16 for start relay S. Relay S thereupon operates and at armature s_1 connects the magnet FDM of the finder switch FS to test wiper 103, at armature s_2 completes a circuit for switching relay K and magnet FDM in series, at armature s_3 opens a point in the circuit of relay CS and at armature s_4 closes a point in a circuit over the connector test wiper 160 which will not be operative at this stage of the connection.
- 20 Since the test contacts associated with lines which are either in use or not calling are connected to earth, switching relay K is short-circuited and magnet FDM is operated in the usual manner and rotates the wipers 101—104 of the 25 finder switch FS until wiper 103 encounters the contact associated with the calling line. When this occurs, no further operating circuit is completed for the magnet FDM; and relay K, being no longer short-circuited, energizes in series with 30 the magnet. Thereupon at armatures k_1 and k_2 it connects the wipers 101 and 102 through to the battery feed relay A, at armature k_3 closes a point in the circuit of relay CS, at armature k_5 removes earth from the test contact in the bank 35 associated with the wiper 109 of the link finder switch JF and prepares a circuit for relay CH, and at armature k_6 connects direct earth via armature k_4 to test wiper 103, whence it is extended via armature l_2 through the lower winding 40 of relay L and the winding of cut-off relay CO to battery. Armature k_6 also applies guarding earth over conductor 10 to the bank of wiper 111 of the distributor DA whence it is extended over 45 the interrupter contacts to the magnet DDM so that this magnet operates to advance the wipers of the distributor in search of the next idle link. Relay CO operates and at armatures co_1 and co_3 disconnects earth and the upper winding of relay L from the speaking leads but relay L remains 50 operated over its lower winding. Relay CO also at armature co_2 opens the start circuit for relay S extending over wiper 110 of the distributor DA and at armature co_4 closes a point in the circuit of the magnet of the meter MT.
- 55 When relay K energizes and extends the circuit of relay A to the line, relay A energizes and at armature a_1 completes the circuit of relay B. Relay B at armature b_1 provides a holding circuit for relay K, which would otherwise release when 60 armature s_2 falls away after its slow release period. Relay B also at armature b_2 completes the initial circuit of metering control relay M, at armature b_3 prepares a circuit for relay CA, at armature b_4 prepares a circuit for the lower 65 winding of relay ST and at armature b_5 opens a point in the circuit of release magnet MRM of the switch MS.
- When relay S has de-energized a circuit is completed at armature s_3 for relay CS which thereupon operates and at armature cs_1 connects the driving magnet JDM of the switch JF to test wiper 109 and at armature cs_2 completes a circuit for relay KA and magnet JDM in series. Magnet JDM now operates to rotate the wipers 70 75 107—109 of the switch JF until wiper 9 engages

the contact from which earth has been removed by the operation of armature k_5 whereupon relay KA is no longer short-circuited and energizes, whereat at armatures ka_3 and ka_6 the junction conductors 20 and 21 extending to the 1st code selector in Fig. 5 are disconnected from conductors 23 and 24 extending to the incoming switch in Fig. 6 and are connected to wipers 107 and 108. Moreover relay KA at armature ka_1 closes the circuit of magnet CDM, at armature ka_2 opens the circuit of relay CS, at armature ka_4 interrupts the connection of magnet JDM to wiper 109, and at armature ka_5 prepares a locking circuit for relay KA over wiper 109. Armature ka_5 also extends earth over wiper 109, conductor 14 and armature k_5 to relay CH which thereupon operates and at armature ch_1 removes earth from conductor 17 and the 25th contact in the bank 111 of the distributor DA. This bank contact number 25 is multiplied to all links wired to its banks so that when all links are engaged i. e. all CH relays operated, the 25th bank contact of wiper 111 will be free from earth and the distributor wipers will rest on the 25th set of contacts to save continuous hunting over engaged 100 contacts.

Moreover relay CH on energizing, at armature ch_2 opens a point in the homing circuit over wiper 159 of the switch LS, at armature ch_3 transfers the circuit of relay M to armature 1 of relay DB, at armature ch_4 completes a local locking circuit for itself and a locking circuit for relay KA, at armature ch_5 closes a point in the test wiper circuit which is not operative at this time, at armature ch_6 prepares impulsing circuits 110 for the switches MS and LS and at armature ch_7 prepares the circuit of relay ST.

Relay DB is now connected in the impulse-out circuit via armature a_2 , conductor 19, wiper 107 of switch JF, armature ka_3 , conductor 20, armatures sw_1 and sd_2 to the upper winding of relay SL and earth; relays DB and SL operate in series with each other. As relay DB operates almost at the same moment that relay CH operates, the operating earth for relay M which was previously provided by armature b_2 is now provided by armature db_1 and ch_3 so that meter-control relay M remains operated.

On the operation of relay SL, Fig. 5, armature sl_1 connects earth via the upper winding of relay 125 SM and armature sk_6 to relay SB which thereupon energizes, while armature sl_2 connects the windings of relays SI and SD across relay SA which operates. Armature sb_1 connects earth to a locking wire which is not effective at this 130 time, armature sb_5 connects earth to conductor 48 and wiper 128 of switch Q and thence via conductor 53 to start relay DAS which energizes.

Armature sb_8 connects up relay SLA over the impulse back conductor 21, armature ka_6 , wiper 135 108 of switch JF, conductor 13, conductor 7 to relay DA, so that relays DA and SLA operate in series. Armature sb_9 connects earth to conductor 25 and bank contact to busy the junction against incoming calls. When impulse-receiving relay 140 DA operates, armature da_1 connects earth from armature ch_6 over the 1st back contact of wiper 164 of switch MS to relay CB which is thereupon energized to prepare a circuit for magnet 145 MDM. Moreover when relay SLA is energized, earth is connected at armature sl_1 to the right-hand winding of electro-polarized relay SD which relay however, does not operate at this time owing to the two windings producing opposing fluxes. Although earth is extended at armature sl_1 via 150

the winding of marginal relay SM to relay SB, relay SM does not operate as the current flowing through its winding is not sufficiently great.

When relays SA and SB operate as mentioned,

- 5 armature *sb6* connects earth via armature *sa1* and wiper 121 to relay SC which operates. Armature *sc7* thereupon removes earth from conductor 43, which connects with bank 126 of switch R, and substitutes the winding of relay SK. When 10 start relay DAS operates as already mentioned, armature *das2* connects the magnet RDM via its interrupter springs and relay DAK in series. The wipers 122—127 of switch R now rotate in known manner until test wiper 126 reaches 15 contact associated with the calling 1st code selector, which contact is free from earth; relay DAK will now be relieved of its short-circuit and will energize. When DAK energizes, it opens the test circuit at armature *dak1*; connects up wipers 20 122, 123, 125, and 127 at armatures *dak5*, *dak7*, *dak6* and *dak8*; and at armature *dak2* extends earth over armature *das2* to wiper 126, conductor 43, armature *sc7* to relay SK which energizes.

- When relay SK energizes, armatures *sk3* and 25 *sk4* switch the holding circuit of relay SA to the loop across wipers 124 and 125; armature *sk1* closes a holding circuit for relay SB through armature *sb1*, while armature *sk6* disconnects the initial energizing potential from relay SB 30 and extends it by way of conductor 47, wiper 127, and armature *dak8* to impulse-receiving relay DDA of the register sender, placing relay DDA under the control of line relay SL; and armature *sk5* disconnects the impulse-back conductor 21 from battery by way of relay SLA and extends it to battery in the register translator, by way of conductor 34, wiper 123, armatures *dak7* and *dc1*, and the associated resistance element. Relay SLA falls back, but the impulse-receiving 40 relay DA in the originating exchange remains operated over the new circuit.

- In the register translator, impulse-receiving relay DDA now operates and at armature *dd1* completes the circuit of release relay DDB which 45 is energized, and the auxiliary release relay DBR is also energized from earth at armature *dab1*.

The register translator represented by Figs. 7, 8 and 9 is now associated with the 1st code selector shown in Fig. 5.

- 50 Relay DBR at armature *dbr3* closes the circuit of the vibrator DV and at armature *dbr8* extends dialing tone over conductor 170 via wiper 144, wiper 124, conductor 41, armature *sk4*, armature *sh1*, armature *sc3* and condenser to the speaking 55 conductor of the 1st code selector, whence it is transmitted over the junction to the calling party as an indication that he may proceed to dial the digits of the number he requires.

- When the calling subscriber's calling device is 60 operated to generate the series of impulses corresponding to the first digit (3), relay A is released and re-operated according to the number of impulses transmitted. Armature *a1* now vibrates and energizes relay CA which maintains relay 65 DB operated at armature *ca1*, and at armature *ca2* connects battery via a low resistance in parallel with supervisory relay DB to improve the quality of the pulses sent to the tandem office; armature *a2* opens and closes the circuit of relay 70 SL in the 1st code selector and armature *sl1* is vibrated in synchronism with the dialled impulses. Armature *sl1* opens and closes the circuit of relay DDA and this relay now transmits, at armature *dd1*, earth pulses via armature *dbr6* 75 to relay DDC, and via wiper 145 and conductor

54 to the two-step counting relays DAD, DBD, and DCD, and to change-over relay DCA. Relay DCA operates responsive to the first impulse and remains operated until the impulses cease. The first impulse passes through armatures *dad2*, *dbd2*, *dcd2*, *dbd3* and *dad3* to the upper winding of relay DAD. Relay DAD is of the two-step type, the first earth impulse received operates armature *dad1* only; when the earth is removed, relay DAD operates fully via its two windings in series over conductor 55, conductor 50, armature *dbr3* to earth, and at armature *dad3* switches the pulsing wire to relay DBD which will operate in a similar manner to relay DAD when the second earth impulse is received. When relay DBD 80 operates fully, armature *dbd4* releases relay DAD, and armature *dbd3* switches the pulsing circuit over to relay DCD. When relay DCD operates fully at the end of the third impulse, it will connect earth via armature *dcd5* to the bank and wiper 130 and magnet CDM which will rotate its wipers 130—137 to the tenth contacts; relay DCA which energizes through its lower winding during pulsing remains energized during automatic rotation of the switch wipers via its upper winding in parallel with the magnet CDM.

At the end of the wiper rotation, relay DCA releases and the second train of impulses will traverse a new circuit over armature *dcd2*, armature *dc1* and armature *dca2* to magnet CDM 105 which will step its wipers three steps in accordance with the second digit (3) of the called party's number.

Relay DDC which operates with each series of impulses connects earth via armature *ddc1* to relay DS which does not release until a short period after relay DDC de-energizes. It follows, therefore, that magnet DDDM of the input-control switch will receive an energizing current which will step its wipers 145, 146 and 147 one 110 step at the end of each series of impulses. When the third series of impulses is received, it follows therefore that wiper 145 will be resting on the third contact and the earth pulses of the third digit (3) will be extended to magnet NAM which 115 will advance its wipers 148 and 149 three steps. The fourth digit (3) will find wiper 145 on the fourth contact and magnet NBM will step its wipers 150, 151 and 152 three steps. As the called party's number consists of four digits only, the 120 full complement of impulses has now been received.

To return to the point where the first and second digits have operated the magnet CDM and its wipers; at the end of the reception of the 130 second digit the wiper 147 is on the second contact and the following circuit for start relay DPR is completed: earth at armature *dbr3*, conductor 50, wiper 147 and bank contact number 2, bank contact 1 and wiper 142 to relay 135 DPR. When start relay DPR energizes, armature *dpr1* opens a point in the circuit of the vibrator DV which releases its armatures. The design of the vibrator is such that when its armature is released magnetically, it vibrates a number of times before coming to rest, due to its own momentum and the design of its restoring spring, in such a manner that armatures *dv1* and *dv2* are opened and closed for the purpose of providing impulses to the circuit to be described. 140

It should be mentioned at this point that when the register translator is taken into use, armature *dbr2* completes a circuit over wiper 143, for relay DC which energizes. When relay DC energizes, armatures *dc1* to *dc4* disconnect the 145 150

- sending circuit, including armature $dv1$, from the loop through wipers 124 and 125 and connect it in the impulse-back circuit, which includes wiper 123 and extends to relay DA by way of junction conductor 21 and conductor 24. In performing this operation, armature $dc1$ opens the normal circuit over wiper 123, and armature $dc3$ closes a holding circuit over wipers 124 and 125. 80
- 10 On the first interruption of armature $dv1$, the circuit over impulse-back conductor 34 is opened and relay DA deenergizes and at armature $da1$ completes the circuit to magnet MDM which advances its wipers one step. Armature $dv2$ 85 will complete the circuit: earth, armature $dbr3$, conductor 50, wiper 47 and bank, armature $ds22$, armature $dv2$, winding of magnet SSDM to battery. Magnet SSDM steps its wipers 138 and 139 one step so that they make contact with the 90 second set of contacts. This series of operations will continue, i. e. pulsing of magnets MDM and SSDM until wiper 138 of switch SSDM finds earth on one of its bank contacts. The translation arranged in the drawing for the first two digits (33) 95 of the called party's number is 3710. The first digit (3) of this translation indicates the zone in which the called subscriber's exchange is situated. When, therefore, wiper 138 has advanced three steps, it will find earth over the following circuit: earth, armature $dbr3$, conductor 50, wiper 147 and bank, wiper 141 and bank (1st contact), wiper 133 and bank contact 13, bank contact and wiper 138 to digit-stop relay DSZ which is energized. Moreover when relay DSZ energizes, armature $ds24$ short-circuits the vibrator armature $dv1$ and opens the circuit over vibrator armature $dv2$ at armature $ds22$; at armature $ds23$ the vibrator is re-energized in readiness for the next series of impulses. 100
- 40 Magnet MDM, having been stepped in synchronism with magnet SSDM, will have advanced its wipers three steps. 105
- Relay DSA operates when wiper 39 of switch SSDM is stepped from its "home" position and armature $dsa2$ now extends earth over conductor 50 via armature $ds21$ to the winding of relay DSZ to provide a temporary holding circuit; armature $ds21$ completes the circuit of magnet CSDM which energizes. Moreover armature $ds25$ extends the earth which is operating DSA via the interrupter springs to magnet SSDM which rotates its wipers until the first contact "home" position is reached whereupon wiper 139 fails to find earth and magnet SSDM stops 110 operating. 115
- Relay DSA also de-energizes after a pause period and at armature $dsa2$ opens the holding circuit of relay DSZ which also de-energizes, while at armature $ds21$ relay DSA opens a point in the circuit of magnet CSDM which advances its wipers 140-144 one step. Moreover, wiper 143 opens the circuit of relay DC which de-energizes and at armatures $dc1$ - $dc4$ recloses the holding circuit over wiper 123; opens the local holding circuit over wipers 124 and 125; and transfers wipers 124 and 125 back to the sending circuit in place of wiper 123. 120
- 73 Armature $ds23$ opens a point in the circuit of vibrator DV which again releases its armatures. Armature $dv1$ opens a point in the circuit of relay SA which de-energizes and at armature $sa1$ completes the circuit of relay SEA and magnet SDM in series both of which are energized. Magnet SSDM energizes over armature $dv2$ and steps its wipers 138 and 139 seven steps whereupon 125 wiper 138 finds earth to energize relay DSZ. At this time magnet SDM has also advanced its wipers 116-121 seven steps, i. e. to the eighth set of contacts. Relay SE energizes in a circuit extending from earth over armatures $sb4$ and $sc2$ and over bank and wiper 120. Relay SE at armature $se1$ closes a locking circuit for itself over the interrupter springs of magnet SDM and armature $sb4$ which is independent of armature $sc2$. Moreover when relay SC releases at the end of the first series of impulses, armature $sc2$ closes a point in a further circuit for relay SEA. Relay SEA is now provided with another holding circuit and magnet SDM is energized. Relay SEA being slow to release does not de-energize when relay SC releases. The interrupter springs of magnet SDM disconnect the circuit of relay SE which, in turn at armature $se2$ opens a point in the circuit of magnet SDM. The wipers 116-121 of switch SDM are now advanced one step, i. e. to the 9th set of contacts. 130
- From this point the subsequent rotation of the SDM switch wipers depends upon the presence of a disengaged trunk to a switch next in the train. In the example shown in the drawings there are three outlets to switches ahead; the bank contacts of wipers 118 and 119 associated with the first two lines are strapped to cause automatic rotation of the switch when the outlets are engaged; the last outlet (No. 3) has the bank of wiper 119 only wired in order to give busy tone when outlets 1, 2 and 3 are engaged. When, therefore, wipers 116-121 reach the 9th set of contacts and the outlet is engaged, earth from the switch ahead will extend over conductor 44, through wiper 118, armatures $sc4$, $sm3$, $sh3$, $sb3$, $sm7$ and $sg3$, interrupter springs, bank and wiper 120 to relay SE which will re-operate and at armature $se2$ again completes the circuit of relay SEA and magnet SDM. Moreover when magnet SDM is energized the interrupter springs open the circuit of relay SE which releases and opens the circuit of magnet SDM; wipers 116-121 now step to the next set of contacts and if conductor 45 is free from earth, indicating that the outlet to the switch ahead is free, relay SE will not re-operate and the short circuit will be removed from relay SH which will energize over the following circuit: earth, armature $sb4$, winding of relay SE, armatures $sm7$ and $sg3$, interrupter springs, bank and wiper 120 winding of relay SE to battery. Relay SE does not, however, energize in series with relay SH. 140
- When relay SH energizes, the talking circuit is switched through to wipers 116 and 117 at armatures $sh1$ and $sh2$ and relay SA releases; the next series of impulses will now be transmitted to the switch next in the train over wipers 116 and 117. 145
- When relay DSZ operates at the conclusion of sending the second digit of the translated code, the previously mentioned pause interval precedes the sending of the third digit 1 which, along with the fourth digit "0", will be transmitted over wipers 116 and 117 to succeeding switches. 150
- At the end of impulsing for the fourth digit, relays DSA and DSZ operate as before and operate the magnet CSDM to step its associated wipers. Now bank contact number 13 of wiper 137 is jumpered to the wire connecting with the normal position contact of armature $dsa2$; relay DSZ will, therefore, remain operated over the circuit: earth, armature $dbr3$, conductor 50, wiper 147 and bank wiper 141 and bank contact number 4, wiper 136 and bank, armature $dsa2$, armature $ds21$, winding of relay DSZ to battery. The 150

switch magnet CSDM will also be energized in series with its interrupter springs, wiper 140 and bank, armature *dbr1* and the circuit previously described. Wipers 140 and 141 will rotate one step until wiper 141 reaches the 6th contact associated with the first numerical storing switch wiper 148, which, as the called party's number is 3333, will be resting on contact number 3.

At this time wiper 141 will have opened the circuit of relay DSZ which will de-energize and allow the vibrator DV to release. The previously described operation of impulsing will now continue until wiper 138 has advanced three steps when it will receive earth from wiper 141 and bank contact. After a pause sending of the final numerical digit will take place.

When the impulses of the last digit have been transmitted and the magnet CSDM has de-energized and stepped its wipers to the 8th set of contacts, the earth which is connected to wiper 141 as previously mentioned will extend over bank contact 8 of wiper 141, bank contact 13 of wiper 132, conductor 49, normal contacts controlled by armature *dco1*, winding of relay DCO to battery. Relay DCO energizes and at armature *dco5* opens a link over wiper 126 and conductor 43 to relay SK. Relay SK de-energizes and at armature *sk6* opens the circuit of relay DDA of the register translator which also de-energizes and in turn opens the circuit of relay DDB and consequently brings down the relays controlled therefrom, including relay DAK. Relay DAK de-energizes and opens the circuits to wipers 122—127 and thereby releases the register translator from the first code selector.

When the called party answers, battery is reversed from the switch ahead to wipers 116 and 117; and polarized relay SD energizes. Relay SD at armature *sd2* disconnects earth through the upper winding of relay SL and connects battery through relay SLB to conductor 20. Relay DB now de-energizes and at armature *db1* opens the circuit of relay M which also de-energizes and at armature *m1* closes a point in the circuit of the upper winding of start relay ST in series with relay MA which is common to a plurality of links. Relays ST and MA are energized and relay ST locks itself at armature *st1* by way of armatures *sp4* and *b4*. Relay MA at armature *ma1* closes the circuit of relay MB; at armature *ma2* closes the circuit of relay MW and at armature *ma3* connects earth to the vibrator MV. Relay MW and the vibrator MV are energized, whereupon armature *mw1* prepares a locking circuit for relay MW, and armature *mw5* closes a point in the circuit of relay MX which, being of the two-step type operates its light armature *mx1* only. At armature *mw1*, earth is extended to armature *mw4*, conductor 31, number 3 bank contact and wiper 166, armature *st4*, conductor 11, wiper 104 and bank, armature *co4* to the meter MT which operates.

Relay MB, which is slow to energize, will now attract its armatures and at armature *mb2* opens the circuit of relay MA to prevent other ST relays operating after the metering operation has started, and at armature *mb1* locks itself up over armature *st2*, while at armature *mb3* it supplies locking potential for relays MW, MX, MY. Moreover when relay MA de-energizes, armature *ma2* opens the original energizing circuit of relay MW and armature *ma3* opens the circuit of the vibrator MV which de-energizes and allows its armatures *mw1* and *mw2* to complete a pendulum movement and produce a series of earth pulses.

When armature *mw2* first releases, the short circuit is removed from the left-hand winding of relay MX which energizes fully over both its windings in series to earth at armature *mb3*, and at armature *mx2* opens the circuit of relay MW which thereupon de-energizes. At armature *mw1* a point is opened in the meter circuit and the meter is de-energized.

On the return swing of the vibrator, armature *mw1* extends earth via *wx5* to the meter which again registers; armature *mw2* extends earth via armatures *my2* and *mx3* to the lower winding of relay MY which is also of the two-step type and operates its light armature *my1* only. When the vibrator again swings to normal armature *mw1* opens a point in the meter circuit and armature *mw2* removes the short-circuit from the upper winding of relay MY which is now fully energized over its two windings in series.

The next return swing of the vibrator will close armature *mw1* to again complete the meter circuit via armature *my3* for the third operation. At the same time, armature *mw2* completes a circuit through armature *my4* for the upper winding of relay SP which will energize partially and operate its armature *sp5* only. When armature *mw1* next releases, the meter circuit is opened and at armature *mw2* the short circuit is removed from the lower winding of relay SP which energizes fully and at armature *sp7* opens the circuit of relay MY which thereupon de-energizes. The meter has now registered three times.

Moreover, when relay SP energizes fully, its armature *sp3* opens the circuit of relay ST which de-energizes and at armature *st4* opens a point in the meter circuit. Armature *sp2* closes the time-period circuit by which magnet TDM receives earth pulses over conductor 171 at intervals of half a minute and advances its wipers 167—169 one step every half minute; armature *st2* opens the locking circuit of relay MB and armatures *st3* and *sp3* complete the dissociation of the common equipment from the circuit.

At the end of a period of two and a half minutes, i. e. when the magnet TDM has received five impulses and advanced its wipers 167—169 five steps, wiper 169 connects a warning tone over conductor 171 to the calling party's line to inform him that the normal period of the call has expired. Moreover, if the call still persists at the end of a further half-minute period wiper 168 will advance to the 7th contact and open the circuit of relay SP which de-energizes and re-connects the common metering equipment to cause further registration on the calling party's meter.

The metering circuit might if necessary be so arranged that a units system of registration could be employed; with this method of metering the revenue would accrue on a strict time period basis with variation in the rate of charge for calls to different zones. For example, it might be arranged that a subscriber's meter should be operated once every 10 seconds during the effective period of a call to zone 1 and twice during a similar period for a call to zone 2 and so on. The circuit for this system of charging calls could be arranged by connecting conductors 31—33 to rotating cams or some other arrangement giving earth pulses at the rate of say 6 per minute for zone 1 (conductor 31) 12 per minute for zone 2 (conductor 32) and 18 per minute for zone 3 (conductor 33). The apparatus shown in Fig. 3 would not then be required.

and the metering wire to wiper 166 would be connected via an armature which would operate when relay CH was energized and an armature on relay M which would close a further point 5 in the circuit when relay M was de-energized. For a call to zone 2, therefore, relay M would de-energize when the called party answered and the meter would be operated every five seconds over conductor 32 which would be connected to 10 an impulse source supplying impulses at the rate of 12 per minute.

When the calling party restores his receiver at the conclusion of the call, relay A is de-energized and at armature a1 opens the circuit of 15 relay B which de-energizes and at armature b1 opens the circuit of relay K which also de-energizes and at armature k6 removes the holding earth which allows relays KA and CH to de-energize. Relay K at armature k4 opens the circuit 20 of relays L and CO which de-energize. Armatures ka3 and ka6 open the junction circuit to the 1st code selector and relay SLA de-energizes and at armature sl1 disconnects the right-hand winding of relay SD. Relay SD de-energizes and at armature sd1 opens the circuit 25 of relay SL which also de-energizes and at armature sl1 opens a point in the circuit of relay SB. Relay SB de-energizes and at armature sb4 removes earth from the lead holding relay SH, at armature sb2 connects earth via the 30 interrupter, springs, bank and wiper 120 to relay SE which energizes and at armature se2 extends earth from armature sb10 to the winding of magnet SDM via relay SEA; magnet SDM advances 35 its wipers 116-120 one step and the interrupter springs open the circuit of relay SE which de-energizes and again completes the circuit of magnet SDM. This sequence of operations will continue and cause the wipers to be advanced until 40 the home position is reached whereupon wiper 120 opens the circuit of relay SE which de-energizes and prevents further rotary motion. The relays in the 1st code selector are now at normal and the switch may be taken from another source for 45 further service.

To return to the point where relay KA de-energized, armature ka1 removes earth from the bank of wiper 106 and allows the junction to be used by other callers, armature ka2 closes a point 50 in the circuit of relay CS which, however, will not operate until another call takes the service of the junction.

In the event of wiper 119 of the 1st code selector reaching the bank contacts of the last outlet 55 let in a group and finding it busy, since there is not strapping between the banks of wipers 118 and 119 in this position wiper 118 would not find earth and the stepping circuit for magnet SDM would be opened, relay SEA would release and at 60 armature seal1 close a point in the circuit of relay SG which would energize from earth over bank contact of the last outlet in the group, wiper 119 and armature seal1 as mentioned. Relay SG at armature sg1 completes a holding circuit for 65 itself to earth at armature sb1 and at armature sg2 extends busy tone over conductor 173 via the condenser to the speaking conductor and thence over the junction to the calling party who is consequently aware that an engaged condition 70 prevents the completion of his call.

Consider now the case in which the calling party dials a non-existent exchange code; in this circumstance the bank of wiper 133, associated with that code, is wired, along with other unused contacts, to the spare code terminal 174.

When wiper 147 of the input control switch DD steps to third position, relay DR operates and at armature dr2 connects battery via a low resistance to wiper 127 in parallel with relay DDA. As a result the current flowing through the winding of relay SM increases to such a value that SM energizes and at armature sm1 locks up to earth at armature sl1. Relay SM at armature sm5 opens a point in the circuit over conductor 47 to relay DDA which de-energizes and opens the circuit of relay DDB. Moreover relay DDB at armature dbb1 opens the circuit of relay DBR which de-energizes and at armature dbr7 removes earth from the windings of relays DAK and SK. 80 85 90

When relays DAK and SK de-energize, the register translator is completely dissociated from the 1st code selector. At armature sm7, relay SM opens the circuit of relay SH (in case it is closed) and places earth from armature sb1 through contacts controlled by armature sg3 and interrupter contacts sdm on all contacts in the bank of wiper 120 except the first and second, while armature sm8 extends this earth potential to the first contact. As a result, relay SE is 100 operated and interacts with driving magnet SDM, as it closes its circuit at armature se2. The wipers 116-121 are driven, therefore, from any position in which they happen to be standing until they reach position two, whereupon wiper 105 120 completes the following circuit: earth, lower winding of relay SG, armature sm6, second bank contact and wiper 120 to relay SE. Relay SG is energized but relay SE is adjusted so that it does not energize in series with the winding of 110 SG. Number unobtainable tone is connected up over conductor 175 at armature sm4 via armature sg2 to condenser and speaking conductor and thence to the calling party, as an indication that the number called is not obtainable. 115

A further condition demanding the number unobtainable tone circuit arises when the calling subscriber, after seizing the register controller and translator, fails to dial; or, after having dialled certain digits, delays the dialling of 120 the remainder for an excessive period. Under this condition the time pulse earth is extended from conductor 176 via the supervisory equipment to the right-hand winding of relay DTP; the time pulse earth is applied for a portion of a 125 second only; and, so long as it remains connected to lead 87, relay DTP will only operate its armature dtp2. When the time pulse earth is withdrawn, relay DTP energizes fully with both its windings in series to earth over conductor 130 50, and at armature dtp1 prepares the circuit of relay DR. The next application of the time pulse earth energizes relay DR which at armature dr2 connects battery to wiper 127 and relay SM. The sequence of operations is the same as 135 described under the previous example.

A further illustration will now be given dealing with a call from subscriber A whose number is 2121 to a second subscriber in the same satellite office whose number will be assumed to be 2129. 14. When the calling subscriber removes his receiver to originate the call, the sequence of operations previously described takes place and the call is extended to the register translator in the tandem office. Relays DDA, DDB, DBR and DC operate as before. The first digit dialled operates relay DAD and then DBD, relay DBD at armature dbd4 opens the circuit of DAD which releases; the magnet CDM does not energize as before, but steps the wipers 130-137 when the 145 150

second digit is received. The single impulse comprising the second digit energizes magnet CDM and the wipers 130—137 are stepped to the second set of bank contacts. Moreover wiper 122 is also resting on the second bank contact as this is the particular calling junction, and if the banks of wipers 122 and 131 are directly multiplied as shown a circuit will be closed for relay DC which, in the example where a satellite 10 subscriber calls a number served by the same office, will remain operated throughout the period during which the register translator is used. The straight multiple shown in the drawings involves the assumption that each satellite exchange 15 has access to the tandem exchange over one junction only though this is of course not essential. When switch R rotates and connects the register controller with that junction and when magnet CDM is so operated by the first two digits dialled by the satellite subscriber that wipers 122 and 131 complete the holding circuit of relay DC, it follows that the calling party has dialled a number served by his local office and that the circuit conditions must be so arranged 20 that all pulses sent out from the register translator are transmitted back over the junction to the calling equipment. Moreover the routing digits normally required to be sent out by the register translator are not required for the particular call being dealt with and armatures *dc5* and *dc8* prepare circuits to absorb these routing digits and allow numerical digits only to be sent. The manner in which this is accomplished 25 will now be described.

When the sending operation is started, the first or metering digit will be sent out over the junction to operate the metering switch in a similar manner to that already described except that this digit will be 1, thereby advancing the minor switch wipers one step and setting them on the 1st zone metering contacts. Moreover, as relay DC does not release in this instance after the first digit has been sent out subsequent impulses will also be transmitted over the junction.

In the particular example shown, where the called party's number is 2129, and the normal translation is 19 for the office code digits 21, the first digit 1 having been sent out, it follows that in normal circumstances the second digit 9 would be transmitted; in the present case where the call originated in office 21, however, the trunking digit 9 is not needed and is absorbed in the following manner. After the sending of the first digit, the stop relay DSZ operates to suspend the sending of impulses and magnet SSDM advances its wipers 138 and 139 to the home contacts; relay DSA now de-energizes and steps wipers 140—144 of the output control switch to the third set of contacts. Relay DSZ remains energized via normal position of armature *dsa2*, armature *dc5*, second bank contact and wiper 141 to earth via bank and wiper 147 and armature *db3*. The magnet CSDM also energizes via its interrupter springs in parallel with relay DSZ and advances its wipers to the next set of contacts; this sequence of operations continues until wiper 141 reaches bank contact number 6 associated with the first numerical digit and fails to find earth whereupon the circuits of magnet CSDM and relay DSZ are opened.

Relay DSZ is de-energized and opens the circuit of the vibrator DV and the impulses of the first numerical digit 2 are sent out over the junction to relay DA which vibrates its armature in response to the impulses and connects earth

via normal position of armature *da1*, normal position of armature *cb1*, wiper 163 and bank, normal positions of armatures *ad5*, *bd4*, *cd3*, *bd5* and *ad3* to the lower winding of relay AD which, being of the two-step type, operates its *ad1* armature only. When armature *da1* returns to its operated position at the end of the first impulse, relay AD energizes fully and prepares the circuit of relay BD which will be energized by the second impulse. Moreover, relay C, which energized initially in parallel with relay AD and remained energized during the two impulses of the digit, now de-energizes and switches the impulse circuit over to magnet LDM via armature *bd4*; relay TD also operates during impulsion.

The next series of impulses for the second numerical digit 9 will be extended via armatures *da1* and *cb1*, wiper 163 and bank, normal position of armature *ad5*, armature *bd4*, normal positions of armatures *c2*, *g6*, *h5*, and *c1* to magnet LDM, while will advance its associated wipers nine steps. Relay E energizes in parallel with magnet LDM and relay TD is again energized and at armature *td1* closes a point in the circuit of relay G. Moreover armature *e3* closes the circuit of relay S which energizes and at armature *s4* closes a further point in the circuit of relay G which is now extended to wiper 160. Relays TD and E are slow to de-energize and if, during the period that they remain operated after the wipers come to rest, relay G receives earth from wiper 160 indicating that the called party's line is engaged it will energize and provide its own locking circuit via armature *g2* and earth at armature *k6* when relay TD de-energizes and restores its armature *td1*. When relay E de-energizes busy tone from conductor 177 via armatures *e4* and *g5* will be connected to the calling party's line, armature *e2* will cause relay KA to de-energize and thereby release the junction for service to other callers. If the called subscriber's line is free, wiper 160 will find battery and when relay TD de-energizes after the second digit, relay H will be energized over the following circuit: earth, armature *k6*, armature *g1*, lower winding of relay H, armature *td1*, armature *s4*, armature *ch5*, wiper 160 and bank to battery over conductor 30 via called party's L and CO relays. Relay H will energize over its lower winding and at armature *h3* complete a locking circuit for itself, and at armatures *h1* and *h2* will connect ringing current through the winding of relay F to the called party's line and the bell will ring; armature *h6* will open the circuit to relay KA which will de-energize and free the junction equipment.

When the called party removes his receiver, direct current will flow through the winding of relay F over the loop and allow relay F to energize. Armature *f3* closes a locking circuit for relay F; armatures *f1* and *f2* complete the talking circuits between calling and called subscribers, while armature *f4* opens the circuit of relay M which de-energizes and completes the metering circuit as previously described.

A further case will now be described in which a call originating in a second satellite exchange is routed to the satellite exchange shown in the drawings. In this case the bank contacts shown at the end of conductors 25—27 will be seized by wipers of a 1st code selector switch which will extend earth to the bank contact and conductor 25 and thence via armature *sb9* to relay SW which will energize and at armatures *sw1* and *sw2* switch conductors 26 and 27 through to

conductors 20 and 21 and the junction. The loop in the 1st code selector will now energize relay BA whereupon armature *ba1* will close the circuit of relay BB which will energize and at 5 armature *bb3* extend earth over conductor 22 to the relevant bank contact of switch CDM (wiper 6) thereby preventing the junction from being taken into use for an outgoing call. Armature *bb1* prepares the impulsing circuit, armature *bb2* 10 opens the homing circuit of magnet BDM, and armature *bb4* prepares the circuits of relays BG and BH. Assuming that the numerical digits of the called party are 43, then when the impulses of the tens digit are received relay BA will vibrate its armature 4 times and relays BAD, BBD and BCD will be energized as follows: At the first 15 impulse, armature *ba1* will connect earth via armature *bb1* and normal position armatures *bad3*, *bbd3* and *bcd3*, to the top winding of relay BC, while a branch circuit extends via normal position armatures *bbd5* and *bad4* to the winding of 20 relay BAD. Relay BC energizes fully but relay BAD operates its armature *bad1* only until relay BA again energizes and removes the short circuit from the upper winding of BAD. Relay BAD now energizes completely and operates all 25 its armatures and at armature *bad5* extends the pulsing lead to relay BBD. The next (2) pulse will operate relay BBD which at armature *bbd2* 30 opens a point in the circuit of relay BAD which de-energizes, and at armature *bbd5* switches the pulsing lead over to relay BCD which energizes with the next (3) impulse and at armature *bcd5* 35 opens a link in the circuit of relay BBD which de-energizes; armature *bcd5* also prepares the holding circuit for relay BAD which is energized by the next (4) impulse. Armature *bcd6* closes a circuit over the first bank contact and wiper 115 for magnet BDM in series with its inter- 40 rupter springs whereupon wipers 112—115 are stepped to the second set of bank contacts where armature *bcd4* has closed a further link in the magnet driving circuit, and the wipers are advanced to the eleventh set of contacts. Armature *bad4* 45 now maintains the driving circuit and the wipers reach the 21st set of contacts where wiper 15 fails to find earth. Relay BC which was energized throughout the first train of impulses remains energized in parallel with magnet BDM during the automatic rotation of the wipers and de-energizes when the driving circuit is 50 opened.

The impulses for the units digit (3) are given via earth at armature *ba1*, armature *bb1*, armature *bad3*, normal position of armatures *bc1*, *bh7*, *bg2* and *bc2* to magnet BDM which advances its wipers three further steps. Moreover relay BE energizes in parallel with magnet BDM and at armature *be4* closes the circuit of relay BS 55 which energizes; armature *be2* closes a point in the circuit of relay BG which is now extended via armature *bs1* to wiper 114.

If the called party's line is engaged, earth on the bank contact associated with his line will 60 extend over wiper 114 to relay BG which will energize. Then, when relay BE releases at the end of its slow release period, busy tone over conductor 178 will be extended via armatures *be3* and *bg4* to the calling party's line.

If the called party's line is disengaged, wiper 65 114 will extend battery to the winding of relay BH when relay BE releases and relay BH will close its own locking circuit at armature *bh1* to earth at armature *bb3*. Armature *bh3* and *bh4* 70 will now extend ringing current via the winding

of relay BF and ringing return battery to the called subscriber's bell which will ring.

When the called party answers, direct current will flow through the winding of relay BF which will energize and at armature *b/3* close its own locking circuit, while at armatures *b/1* and *b/2* 80 it will complete the talking circuits between the calling and called parties.

It should be mentioned that though in the example given, the number of impulses transmitted to effect the setting of the 1st code selector was less than ten, the wiring of the bank of wiper 138 permits the transmission of any number up to 25 since the sender switch is only provided with one normal position. 85

We claim:

1. In a multi-exchange telephone system, a plurality of exchanges, register senders located in one of said exchanges, means including trunk lines interconnecting said exchanges whereby any one of said register senders may be taken into use from any exchange, automatic switches in each of said exchanges arranged to respond to impulses to set up desired connections, and means for operating a register sender to transmit impulses to automatic switches in the same exchange and to transmit impulses to the automatic switches in any other exchange independent of any automatic switches in the same exchange with said register senders. 90

2. In a multi-exchange telephone system, a plurality of exchanges, directly controlled automatic switches in each of said exchanges arranged to set up local and interexchange connections between subscribers' lines, means including interexchange trunk lines whereby, upon the initiation of a call in any one of said exchanges, one of said register senders is taken into use, said register sender being arranged to be set in accordance with impulses received from the line over which it is taken into use and to retransmit impulses to position the necessary automatic switches to complete the desired connection, as indicated by its setting, and means whereby impulses are transmitted from any register sender taken into use to any exchange other than the one in which the register senders are located over a circuit path excluding the directly controlled automatic switches in the exchange in which the register senders are located. 100

3. In a multi-exchange telephone system, a plurality of exchanges, register senders in one of said exchanges, trunk lines interconnecting said exchanges, means responsive to a call in one of said exchanges for setting up a connection over an interexchange trunk line to one of said register senders, means for transmitting impulses to said register sender over said connection, and means in said register sender for transmitting impulses in the opposite direction over said connection to the exchange in which the call originated, and means in the originating exchange responsive to said impulses to set up the desired connection. 110

4. In a multi-exchange telephone system, automatic switches in each exchange, register senders in one exchange, means for sending impulses to said register senders from calling lines in any exchange, and means in said register senders responsive to impulses indicating a desired connection for operating an automatic switch in the exchange in which the register senders are located and for operating an automatic switch in the exchange in which the connection originated over a circuit path excluding the said switch in 115 120 125 130 135 140 145 150 155 160 165 170 175 180 185 190 195 200 205 210 215 the exchange containing the register senders.

5. In a multi-exchange telephone system, register senders located in one of said exchanges and arranged to control the automatic establishment of talking connections, automatic switching apparatus responsive to a call in any one of said exchanges for setting up a connection to any one of said register senders, the number of switches involved in a connection set up from a calling line to a register sender being independent of whether the calling line terminates in the same exchange with the register senders or in another exchange.

6. In a multi-exchange telephone system, a group of local switches in each exchange, a group of tandem switches in one exchange, and means responsive to a call originating on a line of any one of said exchanges for connecting a local switch to said line and for connecting a tandem switch with the local switch.

7. In a multi-exchange telephone system, a group of local switches in each exchange, a group of tandem switches in one exchange, means responsive to a call originating on a line of any one of said exchanges for connecting a local switch to said line and for connecting a tandem switch with the local switch, register senders associated with said tandem switches, and means responsive to any tandem switch being taken into use for connecting any one of said register senders therewith.

8. In a multi-exchange telephone system, a group of local switches in each exchange, a group of tandem switches in one exchange, means responsive to a call originating on a line of any one of said exchanges for connecting a local switch to said line and for connecting a tandem switch with the local switch, register senders associated with said tandem switches, means responsive to any tandem switch being taken into use for connecting any one of said register senders therewith, and means in any register sender taken for use for sending impulses over one circuit path to operate the connected tandem switch and for sending impulses over another circuit path to operate the connected local switch.

9. In a multi-exchange automatic telephone system, register senders located in one of the exchanges of the system and arranged to respond to impulses transmitted thereto from calling automatic lines and to retransmit impulses to the automatic switching apparatus to bring about the setting up of desired connections, said register senders being arranged to form a separate unit and to be connected to the automatic switches in the exchange in which they are located in the same manner in which they are connected to the automatic switches in the other exchanges.

10. In a multi-exchange automatic telephone system, groups of link circuits in one of said exchanges individual to said exchanges, respectively, control devices in the said one exchange common to all of said exchanges, said control devices being associated with calling lines of said exchanges through the intermediation of said link circuits, and means depending upon the exchange group in which a link circuit with which a control device is connected is located for variably controlling the connected control device in accordance with the calling exchange.

11. In a multi-exchange automatic telephone system, link circuits in one exchange arranged in groups, a separate group for each exchange, control devices common to all groups for controlling the automatic establishment of connec-

tions originating in any one of said exchanges, means responsive to the initiation of a call in any exchange to cause one of the corresponding link circuits to associate a control device with the calling line in the calling exchange, means on the said calling line to set up on said control device a registration of the number of the wanted line, and means automatically effective and dependent upon the group in which the instant controlling link circuit is located for setting up in said control device a registration of the exchange containing the calling line.

12. In a telephone system, calling lines arranged in separate groups, link circuits individual to each group, control devices common to all groups for controlling the automatic establishment of connections, means responsive to the initiation of a call for one of said lines to cause one of the corresponding link circuits to associate a control device with said line, said means including a finder switch individual to said controlling device and having access to all of said link circuits, and means dependent upon the set position of said finder switch for setting up in said control device a registration of the group in which the calling line is located.

13. In an automatic telephone system employing register controllers, means responsive to the initiation of a call for connecting a register controller with the corresponding line, said means including a finder switch individual to said register controller, means on the calling line to set up on said register controller a registration of the number of the wanted line, and means dependent upon the position in which said finder switch is set in connecting the register controller with the calling line for modifying the operation of the register controller.

14. In a telephone system employing register controllers, a single-level switch arranged to have access to a plurality of groups of lines leading in different directions, means for transmitting impulses from a register controller to said switch, and means in said switch directly responsive to said impulses for moving the switch into association with the first line in the corresponding group.

15. In a telephone system as claimed in claim 1, means whereby the impulses transmitted to automatic switches in the same exchange are transmitted over a loop circuit and whereby the impulses transmitted to another exchange are transmitted over one talking conductor only.

16. In a telephone system as claimed in claim 1, first numerical switches located in the exchange including said register senders, and means effective whenever an interexchange connection is to be made for operating one of said first numerical switches as the first numerical switch of the interexchange connection.

17. In a telephone system as claimed in claim 12, means for setting up on the control device a registration of the group containing the wanted line, and means controlled jointly in accordance with the registered calling group and the registered wanted group for modifying the operation of the register controller.

18. In a telephone system as claimed in claim 12, means for setting up in said register controller a registration of the group containing the wanted line, two impulse circuits outgoing from said register controller, and means depending jointly upon the registered indication of the calling group and the registered indication of the de-

sired group for determining over which of said two circuits impulses are to be transmitted.

19. In a telephone system a single-level numerical switch having access to a plurality of 5 groups of lines, each of said lines including talking conductors and a test conductor, means responsive to impulses representing a digit of a desired telephone number for positioning the wipers of said switch on the first set of contacts in a desired 10 group, said switch having two test wipers and two corresponding banks of test contacts, one of said test wipers having access to all test conductors of all lines, the other test wiper having access to 15 all of the test conductors of all lines except the last line in each group.

20. In a register sender for use in a multi-exchange telephone system, a single-level exchange-register switch having its bank contacts arranged in groups corresponding to the grouping 20 of the exchanges, means including a group of counting relays responsive to a series of impulses indicating the desired exchange group for advancing the exchange register switch into association with the contact group corresponding 25 to the desired exchange group, and means responsive to impulses corresponding to the desired exchange within the desired group for again advancing said exchange register switch until it comes into association with the contact assigned 30 to the desired exchange.

21. In a telephone system, a single-level automatic switch having access to lines arranged in groups, there being a separate two-digit combination assigned to each of said lines, means responsive 35 to impulses representing the first digit of a two-digit combination and including a set of impulse counting relays for advancing said switch into association with the corresponding group of lines, means responsive to the impulses 40 representing the second digit of the combination for advancing said switch into association with the line to which the two-digit combination is assigned, and means included in the first-named means for preventing the first-mentioned advance of said wipers unless the first digit is represented by more than two impulses.

22. In a telephone system, two automatic switches each arranged to be directly controlled to extend a telephone connection, a register sender, means responsive to a call originating 50 on a telephone line for connecting said line with both of said automatic switches and with said register sender, means in said register sender controlled over the calling line for registering digits in desired telephone numbers, sending means in 55 said register sender operable under the control of the registering means for re-transmitting digit impulses indicative of the desired connection, and means dependent upon the setting of said registering apparatus for determining to which of said automatic switches the digit impulses are to be transmitted.

23. In a telephone system, two automatic switches, a register sender, means responsive to the initiation of a call on a subscriber's line for associating said automatic switches and said register sender therewith, said register sender being arranged to register digits transmitted thereto from the calling line and to control either of said automatic switches, means effective when the registering apparatus of said register sender records a given combination of digits for causing the register sender to operate the first of said automatic switches directly to extend a connection 70 from the calling line, and means effective 75

when the registering apparatus is set in accordance with another digit combination to cause said register sender to directly control the second of said automatic switches to extend the calling line.

24. In a telephone system, two directly controlled automatic switches, means responsive to a call being initiated on a subscriber's line for associating both of said switches with the line, means controlled over said line for operating either of said switches to extend a connection from the line independent of the other switch, and means responsive to one of said switches being completely positioned for disassociating the other switch from the line.

25. In a telephone system, two automatic switches, each of said switches being available for the common use of a plurality of subscribers' lines, means responsive to a call being initiated on any one of said lines for taking both of said switches for use, means controlled over the calling line for directly operating either of said switches to the exclusion of the other to extend a connection from the calling line, and means effective responsive to one of said switches being completely positioned for returning the other switch to common use.

26. In a multi-exchange telephone system, two exchanges, automatic switches in both exchanges, register senders in the second exchange, means responsive to a call being initiated on a line of the first exchange for associating a switch in the first exchange and a switch in the second exchange with said line and for associating one of the register senders in the second exchange 105 with said line, means controlled over the calling line for setting up in said register sender a registration of the desired connection, and means controlled by said register sender in accordance with the registration set up for directly operating the associated switch in either exchange to extend the connection.

27. In a multi-exchange telephone system, two exchanges, automatic switches in both exchanges, register senders in the second exchange, means responsive to the initiation of a call on a line of the first exchange for extending a connection from such line to a register sender in the second exchange, means in the said register sender for registering the desired number under 115 the control of the calling line in the first exchange, and means controlled by said register sender in accordance with the registered number for initially operating an automatic switch in the first exchange or an automatic switch in 120 the second exchange to extend the connection, depending upon the location of the called line as indicated by the registered number.

28. In a multi-exchange telephone system, register senders in a first exchange arranged to 125 control the extension of calls originated on lines entering said exchange, a trunk line interconnecting the first exchange with a second exchange, means responsive to the initiation of a call on a line in the second exchange for extending a connection from said line over said 130 inter-exchange trunk line to a register sender in the first exchange, automatic switching apparatus in the second exchange arranged to be directly operated to extend the connection if a line of the second exchange is being called, and means controlled by said register sender for operating one of said automatic switches in the second exchange over said trunk line to extend 135 the connection.

29. In a multi-exchange telephone system, two exchanges, register senders located in the second exchange, an inter-exchange trunk line interconnecting said exchanges, means responsive to a call originated on a line of the first exchange for extending a connection over said inter-exchange trunk line to a register sender in the second exchange, registering apparatus in the register sender for registering the digits of desired numbers, means for transmitting the digits of the desired number over said inter-exchange trunk line from the calling line to position said registering apparatus, automatic switching apparatus in the first exchange, and means in said register sender for transmitting digits back over said inter-exchange trunk line from the second exchange to the first to operate said automatic switching apparatus to extend a connection from the calling line. 80
30. In a multi-exchange telephone system, two exchanges, an inter-exchange trunk line extending between said exchanges, automatic switching apparatus located in said exchanges and arranged to extend connections from calling lines, register senders in the second exchange, means responsive to a call being initiated on a line of the first exchange for extending a connection from the line over said inter-exchange trunk line to a register sender in the second exchange, means effective when this connection is set up for establishing two impulse channels over said trunk line, means for transmitting impulses over one of said channels from the calling line to position the registering apparatus of said register sender, and means for transmitting impulses back from said register sender over the other of said channels to position automatic switching apparatus in the first exchange to extend a connection from said line. 90
31. In a multi-exchange telephone system, two exchanges inter-connected by a trunk line, register senders in the second exchange, means responsive to a call originating on a line of the first exchange for extending a connection by way of said inter-exchange trunk line to a register sender in the second exchange, automatic switching apparatus in both exchanges, means for establishing a switch-control circuit between the automatic switching apparatus of the first exchange and said register sender and for establishing a separate switch-control circuit between automatic switching apparatus in the second exchange and said register sender, and means in said register sender depending upon the number registered for determining over which of said control circuits the control shall be exercised. 100
32. In a multi-exchange telephone system, two exchanges inter-connected by a trunk line, register senders in the second exchange, means responsive to a call originating on a line of the first exchange for extending a connection by way of said inter-exchange trunk line to a register sender in the second exchange, automatic switching apparatus in both exchanges, means for establishing a switch-control circuit between the automatic switching apparatus of the first exchange and said register sender and for establishing a separate switch-control circuit between automatic switching apparatus in the second exchange and said register sender, and means for transmitting two series of impulses over said control circuits respectively. 110
33. In a multi-exchange telephone system, two exchanges inter-connected by a trunk line, register senders in the second exchange, means responsive to a call originating on a line of the first exchange for extending a connection by way of said inter-exchange trunk line to a register sender in the second exchange, automatic switching apparatus in both exchanges, means for establishing a switch-control circuit between the automatic switching apparatus of the first exchange and said register sender and for establishing a separate switch-control circuit between automatic switching apparatus in the second exchange and said register sender, and means for transmitting two series of impulses over said control circuits respectively. 120
34. In combination, a register sender, means for taking said register sender for use and for setting up a number on the registering apparatus thereof, two separate impulse circuits outgoing from said register sender and means for preparing them for impulses to be transmitted thereover, a sender in said register sender operable to transmit a plurality of series of impulses under the control of the registering apparatus, and means for causing one of said series of impulses to be transmitted over one of said circuits and for causing the remaining ones of said series of impulses to be transmitted over the other of said circuits. 130
35. In combination, a register sender operable to transmit impulses to two separate places, means for taking said register sender into use and for starting it to transmit impulses, a relay and means for operating it to predetermine that the first impulses will be transmitted to the first of said places instead of the other, and means effective following the transmission of the first part of said impulses for restoring said relay so as to cause the remaining impulses to be transmitted to the second of said places instead of to the first. 140
36. In combination, a register sender operable to transmit impulses to two separate places, means for taking said register sender into use and for starting it to transmit impulses, a relay and means for operating it to predetermine that the first impulses will be transmitted to the first of said places instead of the other, means effective following the transmission of the first part of said impulses for restoring said relay so as to cause the remaining impulses to be transmitted to the second of said places instead of to the first, and means effective depending upon the value of the impulses which are to be transmitted for maintaining said relay operated continuously until all of said impulses have been transmitted, whereby all of the impulses are transmitted to the first place and none of them to the second place. 150
37. In an automatic telephone system, a plurality of groups of automatic telephone lines terminating in a plurality of exchanges, respectively, a group of register senders common to all of said groups of lines and arranged to be controlled over any line to register the digits of desired telephone numbers and to control the setting of the automatic switches in accordance with the registered digits, each of said register senders being arranged to operate in either of two distinct manners, and means effective when a register sender is in use and depending jointly upon the group in which the line with which it is being used is located and the number transmitted to the registering apparatus of the register sender from said line for determining in which 160

of said two manners the register sender will operate.

38. In an automatic telephone system, a plurality of groups of subscribers' lines, a like plurality of groups of final selectors having direct access to said groups of lines respectively, group selectors, means effective when a call is originated on any one of said lines for associating a final connector in the corresponding group with said line and for associating one of said group selectors therewith, means effective in case the number dialled by the subscriber on the calling line is the number of a line in some other group for completing the connection to the called line by way of said group selector and a final selector in the group assigned to the line group containing the called line and without operating the final selector which has been brought into association with the calling line, and means effective when the number dialled by the calling subscriber is the number of a line in the same group for operating the final selector which has been associated with the calling line to complete the connection to the called line without operating said group selector.

39. In an automatic telephone system, a plurality of groups of subscribers' lines, a like plurality of groups of final selectors having direct access to said groups of lines respectively, group selectors, means effective when a call is originated on any one of said lines for associating a final connector in the corresponding group with said line and for associating one of said group selectors therewith, means effective in case the number dialled by the subscriber on the calling line is the number of a line in some other group for completing the connection to the called line by way of said group selector and a final selector in the group assigned to the line group containing the called line, means effective when the number dialled by the calling subscriber is the number of a line in the same group for operating the final selector which has been associated with the calling line to complete the connection to the called line, and means responsive to the complete positioning of the final selector for freeing the group selector.

40. In an automatic telephone system, two groups of automatic switches arranged to extend telephone connections, means responsive to a call being initiated on a calling line for connecting a switch of the first group with the calling line and for separately connecting a switch of the second group to the calling line, means on the calling line for transmitting impulses in accordance with the number assigned to the desired called line, and means responsive to said impulses for operating the first of the connected switches to extend the call while the second switch remains unoperated, and means effective in case the digits dialled indicate a different called line for operating the second connected switch to extend the connection while the first connected switch remains unoperated.

41. In a multi-exchange telephone system, automatic switches in each of two exchanges, and means controlled over a calling line in the first exchange for operating any one of said switches to make the initial and sole directive extension of said calling line toward a called line.

42. In a telephone system, a single-motion switch arranged to have access to a plurality of groups of lines extending in different directions, means for transmitting impulses to said switch, and means in said switch for moving the switch

into association with the first line in the corresponding group directly responsive to said impulses.

43. In a telephone system wherein the connections are set up through directly operable single-motion switches, a single-motion switch having access to groups of lines of different sizes, means for causing said switch to rest normally in its home position, means for transmitting impulses to said switch to cause it to move from its home position into association with the several groups successively, whereby it is brought into association with a desired group, and means for causing said switch to respond to more impulses in advancing across a large group of contacts than it does to advance across a smaller group of contacts.

44. In a single-motion selector switch for use in a telephone system, the contacts in the bank of said selector switch being divided into groups, each group being connected to a different group of lines and being indexed by a separate digit, the digit indexing a group being the sum of the impulses required to be delivered to said switch to drive it from its home position over the preceding groups, and means for delivering a larger number of impulses to said switch to drive it over a large group than to drive it over a smaller group, whereby the digit indexing a given group of contacts depends jointly upon the number of preceding groups and the number of lines in the respective groups.

45. In a telephone system, single-motion selector switches arranged to extend connections from subscribers' lines responsive to impulses transmitted by calling devices on the subscribers' lines, the contacts in the bank of said selector being divided into separate groups, each group indexed by a digit depending jointly upon the number of preceding contact groups and the number of contacts in such groups, a register sender interposed between the calling lines and said selector, and means in said register sender for introducing a translation between the registering apparatus and the sending apparatus so that the series of impulses delivered to a selector to bring it into association with a desired contact group may exceed the number of impulses which can be sent from a subscriber's calling device in a single series, thereby enabling as many contacts as desired to be assigned to each of the groups preceding the final contact group of the selector.

46. In combination, a single-motion automatic switch having its contact bank divided into groups, each group corresponding to a separate digit, means for delivering two series of impulses to said automatic switch, means at the switch responsive to the first series of impulses for advancing the wipers of the switch into association with the contact group indexed by the digit to which the impulse series corresponds, means responsive to the second series of impulses for further advancing the wipers of the switch until they come to rest on the desired contact set in the desired group, and means for absorbing a plurality of impulses of the first series, whereby the digit values assigned to the contact groups are increased.

47. In combination, an automatic switch having a set of wipers and a contact bank therefor, the contacts in said bank being divided into groups, each group being indexed by a separate digit, means for transmitting a series of impulses to said automatic switch, means responsive to said series of impulses for positioning the wipers

- in relation to the contact group bearing the corresponding digit designation, and means for absorbing the first impulses of the series until a plurality have been absorbed, whereby the digit 5 values assigned to the respective contact groups are increased.
48. In combination, an automatic switch having a set of wipers and a contact bank therefor, the contacts in said bank being divided into 10 groups, each group being indexed by a separate digit, means for transmitting a series of impulses to said automatic switch, means responsive to said series of impulses for positioning the wipers in relation to the contact group bearing the corresponding digit designation, there being no contact group corresponding to the digit one, and means for absorbing the first impulse of a series 15 without operating the wipers of the switch, whereby the first contact group in the bank of the switch has a digit value greater than one.
49. In combination, an automatic switch arranged to be positioned responsive to a train of impulses, a set of counting relays associated with said switch and arranged to be operated successively responsive to the succeeding impulses of a series as they are received and to position the switch in accordance with the number of received impulses, there being fewer counting relays than there are impulses in the maximum train to be 20 received, and means for operating one of said relays to count more than one of said impulses.
50. In combination, an automatic switch arranged to be positioned responsive to a train of impulses, a set of counting relays associated with 25 said switch and arranged to be operated successively responsive to the succeeding impulses of a series as they are received and to position the switch in accordance with the number of received impulses, there being fewer counting relays than there are impulses in the maximum train to be received, and means for re-operating one of said counting relays to count a second impulse after 30 it has been once operated to count a first impulse.
- 45 51. In combination, means for generating a plurality of series of impulses, a set of counting relays arranged to count one series of impulses, a slow-acting change-over relay arranged to be operated at the beginning of the series of impulses counted by said counting relays, and means including counting relay contacts and contacts of said slow-acting relay whereby the falling back of said slow-acting relay at the end of the series of impulses removes said counting relays from 55 under the control of the impulse generating device.
52. In combination, an automatic switch arranged to receive two series of impulses, counting relays in said switch arranged to respond to 60 the first series of impulses, an operating magnet in said switch arranged to respond to the second series of impulses, a slow-acting change-over relay arranged to be operated responsive to the first series of impulses and to remain operated 65 throughout, and means including counting relay contacts and contacts of said slow-acting relay and effective when the slow-acting relay falls back at the end of the first series of impulses for preventing the counting relays from responding 70 to the second series of impulses and for enabling the operating magnet to respond to the said second series.
53. In a telephone system, a finder-connector link arranged to complete connections between 75 calling lines and called lines, a start relay and means for operating it to start the finder of said link searching for a calling line, means for operating said connector from the calling line and through the finder to bring it into association with the contacts of the desired called line, said connector having a normally disconnected test wiper, and means operated during the final positioning of said connector for re-operating said start relay to connect up said test wiper. 80
54. In combination, a single-motion automatic switch having access to lines divided into groups, each group corresponding to an impulse series of different value, means for sending a series of impulses to said switch, means responsive to one series of impulses for advancing said switch into association with the group of contacts corresponding to the series of impulses, means responsive to the next series of impulses for advancing said switch into association with the line in the selected group corresponding to the received series of impulses, a first slow-acting relay and means for energizing it throughout the last received series of impulses, a second slow-acting relay and means for maintaining it energized while the first slow-acting relay is energized, 100 whereby the last-mentioned slow-acting relay is the last to release, means for preventing the last-named slow-acting relay from being energized while the first-named series of impulses is being received, and a test circuit for testing the selected line controlled jointly by said slow-acting relays. 105
55. In combination, a connector switch having access to lines divided into groups and arranged to be set into relation with the desired group of lines responsive to one series of impulses and to 110 be set on a desired line responsive to a subsequent series of impulses, a test wiper for said switch normally disconnected therefrom, a slow-acting relay and means for energizing it initially during the second series of impulses and for 115 maintaining it energized throughout, and means controlled by said relays for connecting up said test wiper to enable the called line to be tested when reached, whereby the line on which the wiper rested at the end of the first movement 120 was not tested.
56. In a telephone system, two exchanges inter-connected by a trunk line, an automatic switch in the second exchange, means in the first exchange for setting up a connection from the 125 first exchange through the said trunk line to said automatic switch in the second exchange and for establishing two separate impulse circuits over said trunk line, separate means for sending impulses over each of said impulse circuits, 130 means for operating said automatic switch responsive to impulses sent over one of said circuits, and means for releasing said automatic switch controlled over either of said circuits.
57. In a telephone system, means including an 135 automatic switch for setting up a connection by way of a trunk line from a calling telephone line to a called line, a supervisory relay associated with said automatic switch and arranged to be operated under the control of the called line, 140 means controlled by the supervisory relay for indicating in the direction of the calling line the supervisory condition existing on the called line and for preventing said automatic switch from being released as long as said supervisory relay 145 is operated, and means controlled over the calling line for releasing said supervisory relay to bring about a release of said automatic switch.
58. In a telephone system employing register senders, trunk lines, means controlled over a 150

calling line for extending a connection from the calling line to one of said trunk lines and for setting up a connection from the trunk line to one of said register senders, said connection including a plurality of conductors, means for sending impulses from the calling line by way of said trunk line to said register sender by way of one of said conductors to position the registering apparatus of said register sender, a marginally adjusted relay associated with said trunk line arranged not to operate when impulses are being transmitted to the register sender, and means in said register sender responsive to an abnormal condition for causing an increased current flow to take place over said conductor through said marginal relay to bring about its operation.

59. In a telephone system as claimed in claim 58, and means controlled by said marginally adjusted relay for transmitting a special tone signal 20 back to the calling line indicative of the abnormal condition.

60. In an automatic telephone system wherein

connections from calling lines to called lines are set up by way of trunk lines, means responsive to one of said trunk lines being taken for use for associating a register sender with such trunk line to record the number dialled by the calling subscriber and to send impulses to effect the setting of the switching apparatus, a relay in said trunk line, means for operating said relay under the control of the register sender responsive either to a non-existing number being dialled or to a delay in dialling, and means in the trunk line for operating said relay responsive to the calling subscriber starting to dial the number before the register sender has been associated with the trunk line.

61. In a telephone system as claimed in claim 60, means controlled by said relay whenever it is operated for sending a distinctive tone signal back to the calling line.
